STRUCTURE FOR FURNITURE AND THE LIKE

Justin J. Wetzler, Evanston, Ill., assignor to The Englander Company, Inc., Chicago, Ill., a corporation of Delaware

Application June 21, 1954, Serial No. 438,254

6 Claims. (Cl. 155—180)

The present invention relates to a novel structure adapted to be used in pieces of furniture such for example as chairs, divans, couches, beds, or vehicle seats, and more particularly to a novel structure for attaching covering fabrics and the like to frame members of such pieces of furniture. The present application is a continuation-in-part of my copending application Ser. No. 419,736, filed March 30, 1954.

As set forth in my above mentioned copending application, frames for box spring units of various pieces of furniture and separate box spring units for use in beds and the like as well as frame members for arms, backs and other portions of various pieces of furniture have generally been made from wood in the past. When wood is used for the frame or frame members covering fabrics may easily be secured thereto by means of tacks, staples or the like. The present invention, however, contemplates the use of metal frame members so that covering fabrics cannot be secured thereto by means of tacks, or other similar securing devices. It is, therefore, a primary object of the present invention to provide a novel structure for use in box spring units or various pieces of furniture, which structure includes a metal frame member and a covering fabric, and wherein the fabric may be easily secured to the metal frame member in a novel and economical manner.

A more specific object of the present invention is to provide a novel metal frame member for box spring units or various pieces of furniture, which frame member is formed so that a covering fabric or the like may be easily attached thereto without the aid of separate securing means.

Other objects and advantages of the present invention will become apparent from the following description and the accompanying drawings wherein:

Fig. 1 is a fragmentary perspective view showing a portion of a frame member and sections of fabrics secured to the frame member in accordance with the present invention;

Fig. 2 is an enlarged fragmentary cross sectional view taken along line 2—2 in Fig. 1;

Fig. 3 is a fragmentary perspective view similar to Fig. 1 but showing a slightly modified form of the present invention;

Fig. 4 is an enlarged fragmentary cross sectional view taken along line 4—4 in Fig. 3;

Fig. 5 is a fragmentary perspective view showing another slightly modified form of the present invention; and

Fig. 6 is an enlarged cross sectional view taken along line 6—6 in Fig. 5.

Referring now more specifically to the drawings wherein like parts are designated by the same numerals throughout the various figures, a structure 10 embodying the principles of this invention is shown in Figs. 1 and 2. This structure includes a metal frame member 12 which may be used for forming the frame of a box spring unit in the manner shown and described in the above mentioned copending application and which also may be

2

used to provide the frame for arm rests or back rests of various chairs or divans and the like, not shown. In addition, the structure 10 includes a covering fabric 14 and when the structure 10 is to be used in a box spring unit or the like the bottom of the frame may be closed by a fabric 16 to protect against the entry of dust.

The frame member 12 includes upper and lower flanges 18 and 20 which are joined together by a web 22. A longitudinally extending mid-portion of the web is formed 10 to provide a channel which includes inwardly extending sections 24 and 26 that are parallel to the flanges 18 and 20 and a connecting section 28. The advantages and various uses of the frame member 12 have been fully set forth in the above mentioned copending application and need not be repeated here.

In accordance with the present invention the frame member 12 is provided with simple integral means for attaching the covering and dust protecting fabrics thereto rapidly and easily, and, therefore, economically. More specifically, a plurality of pointed barbs or prongs 30 are struck from the lower flange 20 of the frame member. As shown best in Fig. 2 the prongs 30 extend downwardly from the flange 20 and also inwardly of the frame member. Thus, the covering fabric 14 may be easily attached to the frame member by forcing the prongs through the margin of the fabric. As will be understood opposite margins of the fabric will be secured to opposite sides of the frame so that the covering fabric is under sufficient tension to prevent it from becoming disassembled from the prongs 30. While only a short section of the frame member 12 is shown in the drawings, it will be understood that the frame member may be of any desired length and that the prongs 30 are spaced along substantially the entire length of the frame member for evenly retaining substantially all marginal portions of the covering fabric.

In order to secure the dust protecting fabric 16 to the frame member a series of pointed barbs or prongs 32 are struck from the bottom flange 20. The prongs 32 are similar to the prongs 30 except that they are inclined downwardly and outwardly of the frame member as shown best in Fig. 2. It will be appreciated that the fabric 16 may be secured to the prongs 32 in substantially the same manner as the covering fabric is secured to the prongs 30. It should be noted that the prongs 30 and 32 are preferably disposed adjacent each other and in opposing relationship since this arrangement facilitates and simplifies the forming dies, not shown, and procedure required to strike the prongs from the flange. It should also be noted that the margins of the fabrics 14 and 16 through which the prongs extend are preferably folded to at least a double thickness as shown in Fig. 2 whereby substantially to eliminate any possibility of tearing the fabrics.

In Figs. 3 and 4 there is shown a structure 10a which is similar to the above described structure 10 as indicated by the application of identical reference numerals with the suffix *a* added to corresponding elements. This embodiment of the present invention differs from the above described structure only in that the above mentioned dust protecting fabric 16 and the prongs 32 for securing the dust protecting fabric have been eliminated. Thus, the frame structure 10a is especially adapted for use whenever the dust protecting fabric may be eliminated either because it is not needed or because it is desired to provide a more economical structure.

Figs. 5 and 6 show another modified embodiment of the present invention which is similar to the above described structure 10 as indicated by the application of identical reference numerals with the suffix *b* added to corresponding elements. In this embodiment the above described prongs 30 and 32 have been replaced by similar

pointed barbs or prongs 34, which prongs 34 are inclined upwardly from the flange 20b and outwardly relative to the frame member as shown best in Fig. 6. With this arrangement of the prongs 34 the covering fabric 14b is wrapped around the flange 20b for application to the prongs. Thus, the appearance of the fabric covering the exterior surface of the flange 20b is not marred by projecting prongs as it would be with the structures of the above described embodiments, and the arrangement of the prongs 34 has the further advantage of eliminating any possibility of a person being cut or scratched when lifting the frame member 12b by gripping the flange 20b or when moving a portion of his body such as his hand along the exterior surface of the flange 20b for any desired reason. The prongs 34 may also be utilized to secure a dust protecting fabric 16b in the manner shown and, therefore, the embodiment of Figs. 5 and 6 has the still further advantage in that the same prongs may be utilized for securing both the covering fabric and the dust protecting fabric.

From the above description it is seen that the present invention has provided a novel structure which is fully capable of satisfying the objects heretofore set forth. More specifically it is seen that the present invention has provided a novel metal frame member for use in box spring units or other frame portions of various pieces of furniture, which frame member is formed so that one or more fabric sections may be easily and economically secured thereto without the aid of separate fastening means.

While the preferred embodiments of the present invention have been shown and described herein it is obvious that many structural details may be changed without departing from the spirit and scope of the appended claims.

The invention is claimed as follows:

1. A structure of the type described for use in furniture comprising a sheet metal frame member, a plurality of fabric sections extending in opposite directions from said frame member, and projection means integral with and struck from said frame member and embedded in said fabric sections for attaching the fabric sections to the frame member.
